US00D815862S

(12) **United States Design Patent** (10) **Patent No.:** **US D815,862 S**
(45) **Date of Patent:** **** Apr. 24, 2018**

(54) **PILLOW**

(71) Applicant: **TAKASHIMA CO., LTD.**, Osaka (JP)

(72) Inventor: **Hisato Takashima**, Takatsuki (JP)

(73) Assignee: **Takashima Co., Ltd.**, Osaka (JP)

(**) Term: **15 Years**

(21) Appl. No.: **29/591,928**

(22) Filed: **Jan. 25, 2017**

(30) **Foreign Application Priority Data**

Jul. 29, 2016 (JP) 2016-016241

(51) **LOC (11) Cl.** **06-09**

(52) **U.S. Cl.**

(57) **CLAIM**

The ornamental design for a pillow, as shown and described.

DESCRIPTION

FIG. 1 is a perspective view of a pillow showing my new design;

FIG. 2 is a front elevational view thereof, the rear view being an identical image of FIG. 2;

FIG. 3 is a top plan view thereof;

FIG. 4 is a bottom plan view thereof;

FIG. 5 is a right side elevational view thereof, the left side view being an identical image of FIG. 5;

FIG. 6 is a cross sectional view taken along line 6-6 in FIG. 2; and,

FIG. 7 is a perspective view showing the article in use. The features shown in broken lines in FIGS. 6 and 7 depict environmental subject matter and form no part of the claimed design.

1 Claim, 7 Drawing Sheets
